PHOTOELECTRIC EXPOSURE CONTROL ATTACHMENT OR SIMILAR ARTICLE

Sidney H. Bradd, Jr., New York, and Robert H. Ensign, Bronxville, N.Y., and Richard R. Wareham, Marblehead, Mass., assignors to Polaroid Corporation, Cambridge, Mass., a corporation of Delaware

Application October 14, 1958, Serial No. 52,975

Term of patent 14 years

(Cl. D61—1)

Figure 1 is a front elevational view of a photoelectric exposure control attachment or similar article, showing our new design;

Fig. 2 is a front perspective view; and

Fig. 3 is a rear perspective view thereof.

The dominant features of our new design are shown in solid lines in the drawing. Portions of Figures 1 and 2 showing gridded areas also include diagonal lines to indicate transparent covering of said areas.

We claim:

The ornamental design for a photoelectric exposure control attachment or similar article, substantially as shown and described.
